(57) **CLAIM**

We claim the ornamental design for a sleeve, substantially as shown and described.

DESCRIPTION

FIG. 1 is a perspective view of a first embodiment of a sleeve showing our new design.

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a perspective view of a second embodiment of a sleeve;

FIG. 9 is a front view thereof;

FIG. 10 is a rear view thereof;

FIG. 11 is a top view thereof;

FIG. 12 is a bottom view thereof;

FIG. 13 is a left side view thereof; and,

FIG. 14 is a right side view thereof.

The zig zag lines shown on the edges of the sleeve represent a specific pattern of stitching.
